UNITED STATES PATENT OFFICE

ALEXANDER S. KATZ, OF BROOKLYN, NEW YORK

DESIGN FOR A HINGE OR SIMILAR ARTICLE

Application filed September 5, 1931. Serial No. 41,036. Term of patent 7 years.

To all whom it may concern:

Be it known that ALEXANDER S. KATZ, a citizen of the United States, and resident of Brooklyn, New York, in the county of Kings and State of New York, has invented a new, original, and ornamental Design for a Hinge or Similar Article, of which the following is a specification, reference being had to the accompanying drawings forming part thereof, in which—

Fig. 1 is a front view of a hinge or similar article embodying my new design; and
Fig. 2 is a side elevational view thereof.

I claim:

The ornamental design for a hinge or similar article, substantially as shown.

Dated Brooklyn, New York, September 3, 1931.

ALEXANDER S. KATZ.
